UNITED STATES PATENT OFFICE.

JOHN ALONZO TRAYLOR, OF DENVER, COLORADO.

PACKING-RING FOR ROTARY PUMPS.

No. 893,113.

Specification of Letters Patent.

Patented July 14, 1908.

Application filed July 17, 1906. Serial No. 326,591.

To all whom it may concern:

Be it known that I, JOHN ALONZO TRAYLOR, a citizen of the United States of America, residing in the city and county of Denver and 5 State of Colorado, have invented a new and useful Packing-Ring for Rotary Pumps, of which the following is a specification.

My invention relates to packing the space between the lining and the casing of rotary 10 pumps, and the object of my invention is; to so pack the pump between its lining and its casing as to stop the circulation of the water in the space between them. I attain this object by the mechanism illustrated in 15 the accompanying drawings, in which:

Figure 1, is a vertical longitudinal sectional view through a rotary pump showing my improved packing ring applied thereto. Fig. 2, is a vertical transverse sectional view 20 through the pump. And Fig. 3, is a vertical sectional view of a portion of a pump showing a modification in the form of the ring.

Similar letters of reference refer to similar parts throughout the several views.

Referring to the drawings, the numeral 1, 25 designates the outside casing of a rotary pump, and 2 designates the lining of the pump. Both the pump and its casing are provided with suction inlet apertures 3 and 4 respectively, and with outlet discharge aperture portions 5 and 6 respectively. The lining is hollow, and within it is journaled a rotary piston, which I do not illustrate. The lining fits loosely within the casing, it being 30 centrally within a channel 7, formed in the casing. The casing is made in two halves, which are bolted together, thus inclosing the lining. The channel 7, in which the lining is placed, is made larger than the lining; con- 35sequently a space is formed between them. This space extends throughout the lining, and casing, and the lining is held centrally in the channel by set-screws and bolts 9. The piston and the lining and the casing, as co- 40operating to form an operative water pump- 45ing. This space or channel 7, forms a pas- sage for water, which is drawn into it and circulated through the pump and out of it along with the discharging water, which is objectionable, as when pumping sandy water 50 the sand cuts out the casing, which is made of soft cast iron, while the lining is made of

chilled cast iron. I accomplish this in the following manner: In the mouth of the discharge aperture of the discharge outlet of the casing, I form a circumferential groove 10, 60 preferably using a rectangular groove, which I preferably extend into the mouth of the aperture from its end, and I enlarge the adjacent end of the lining, which fits loosely but closely the mouth of the casing, at its 65 mouth, and extends to the end of the discharge aperture of the casing, and in its peripheral surface I also form a circumferential groove 11, which I position opposite the groove 10 in the casing, in the extreme side 70 and front edge of the lining. If preferred, however, the packing groove may be placed at a short distance inside of the mouth of the casing and lining, as shown in Fig. 3, in which case a round packing 12, is preferably used, 75 necessitating semicircular shaped slots in the casing and lining. In the preferred construction I preferably use the square packing 13, and as the packing recesses extend in from the face of the casing and lining, the 80 packing 13, is inserted from the outside of the pump after the halves of the casing are bolted together around the lining, while in the form shown in Fig. 3, the packing is placed around the head of the lining at the 85 time it is laid in one-half of the casing before the other half is placed over it, and the halves are bolted together. In the preferred construction, the packing is forced into the packing recesses, and when the flange 14 of 90 the delivery pipe 15, is bolted to the flange 16, of the casing, the packing is confined against accidental displacement.

My improved packing makes a perfectly 95 water-tight joint around the lining and be- 95tween it and its surrounding casing, and effectually stops the circulation of water be- 100tween them.

Having described my invention, what I 100 claim as new and desire to secure by Letters Patent, is:

1. A packing device for the linings of rotary pumps, the combination with the casing and the lining having a space between them of a circumferential groove encircling said lining, 105 a similar groove in the inner periphery of said casing registering with the groove in said lining, and a suitable packing material packed in said grooves.

2. A packing device for the linings of ro- 110tary pumps, comprising a rotary pump cas- ing, and a rotary piston lining within said

casing, of an enlarged ring portion at the terminal end of the discharge aperture of said lining, a circumferential packing receiving groove in the periphery of said ring portion, 5 a flanged terminal discharge aperture on said casing surrounding the discharge ring end of said lining, a packing receiving recess in the inner periphery of said casing registering with the packing recess in said lining, and a 10 packing ring packed in said recesses to close the joint between said lining and said casing.

3. A packing device for the linings of rotary pumps, the combination with the casing, having on its inner periphery a circumferential 15 packing receiving recess, of the lining having a peripheral recess adapted to receive a packing registering opposite the packing recess of said casing, a space in said casing surrounding said lining and a suitable packing packed 20 in said recesses and arranged to close the joint between them.

4. In a packing device for the linings of rotary pumps, the combination of the casing having a channel, a piston lining loosely secured in the channel of said casing, said casing being provided with a space surrounding 25 said lining a packing recess formed partially around the lining and partially around the inner periphery of said casing in said channel, 30 and a suitable packing packed in said packing recess.

5. In a packing device for packing the linings of rotary pumps, the combination of the casing, having a channel, a flange at its water 35 delivering outlet aperture, and a delivery pipe flange secured to the flange of said casing, with the piston lining fitting loosely in the channel of said casing said casing being provided with a space surrounding said piston 40 lining and having a discharge outlet aper-

ture terminating at the end of said casing's flange, a circumferential packing recess in the peripheral edge of said lining, a similar packing recess formed in the inner periphery of the entrance of said flanged outlet of said 45 casing, said recess in each being open to the under side of said delivery pipe's flange, and a suitable packing packed in said recesses of said lining and casing and adapted to be confined therein by said delivery pipe flange. 50

6. In a packing device for the linings of rotary pumps, the combination with the casing and the lining said casing being provided with a sand-holding space surrounding said lining of the packing recesses and the packing operatively arranged to close the joint between them. 55

7. In a packing device for the linings of rotary pumps, the combination of the casing provided with an interior lining holding space 60 and having a flange at its discharge outlet aperture, and the lining fitting in said casing in such a manner as to leave a sand-filling space between it and the inner peripheral wall of said casing, said lining being provided 65 with an enlarged ring and extending to and registering even with the face of said flange, with the packing recess formed partially on said flanged inlet and said ring end from the outside of said flange and said ring end, the 70 packing in said packing recess, and the delivery pipe flange bolted to said casing flange and adapted to securely pack and hold said packing in said recess.

In testimony whereof I affix my signature 75 in presence of two witnesses.

JOHN ALONZO TRAYLOR.
